UNITED STATES PATENT OFFICE.

FRANK WHARTON, OF ELYRIA, OHIO.

SHOE-HEEL.

1,300,070.

Specification of Letters Patent.

Patented Apr. 8, 1919.

Application filed May 20, 1918. Serial No. 235,661.

To all whom it may concern:

Be it known that I, FRANK WHARTON, a citizen of the United States, residing at Elyria, in the county of Lorain and State of Ohio, have invented new and useful Improvements in Shoe-Heels, of which the following is a specification.

This invention relates to shoe heels and aims to provide a heel constructed of rubber or other compressible material which may be easily and readily attached to or removed from the shoe.

The primary object of the invention is to provide a heel of this character with an auxiliary cushioning means in the form of a raised portion extending beyond the tread surface of the heel, the heel being hollowed out or provided with a cavity upon its upper surface at the rear of the raised portion to permit the latter to yield under pressure and a resilient or compressible stop located within the cavity for contact with the attaching plate or rigid portion of the shoe to yieldingly limit the inward movement of the auxiliary cushion.

Other objects and advantages of the invention will appear as the following description is read in connection with the accompanying drawings, in which:

30 Figure 1 is a perspective view of a heel constructed in accordance with the invention;

Fig. 2 is a plan view of the attaching plate;

35 Fig. 3 is a transverse sectional view showing the plate and heel secured together.

Referring to the drawings in detail, wherein like characters of reference denote corresponding parts, the heel is shown at "A" and the attaching plate at "B."

40 The plate may be formed of any suitable material, aluminum being preferred on account of its lightness. The plate "B" is concaved upon its upper surface and is provided upon its lower surface with a surrounding flange or tongue 10, the latter being preferably V-shaped in cross section for engagement with the heel "A" which will be hereinafter apparent. The plate "B" is further 45 provided with a plurality of apertures 11 for the passage of nails or other fastening devices, by means of which the said plate may be secured to the heel portion of the shoe.

55 A heel "A" which is preferably formed of rubber or other compressible material is of

the same size and shape as the plate "B" and is provided around its upper edge with a groove 12 which is adapted to receive the tongue 10 to removably secure the heel and 60 plate together. To provide against the accidental detachment of the heel, the latter is provided upon its upper surface which is concaved as shown, with a hook member 13. This member is adapted to engage a slot 14 65 formed in the plate "B," one edge of the slot being beveled at 15 to more readily wedge the hook in position.

The hook member is formed of a strip of metal, having each of its ends bent at right 70 angles in opposite directions, one of said ends form the hook 13, while the other end provides an anchor 13^a. This latter end is flared outwardly as shown in Fig. 5 so as to more readily embed itself into the material 75 of which the heel is made. The hook member is formed with openings 13^b, so that when the said member is molded in the heel, the rubber or other material will enter the said openings and form additional anchor- 80 ing means.

A particular novel feature of the invention resides in providing an auxiliary cushioning means, which in addition to absorbing the shock or jar due to contact with the 85 surface walked upon also acts to prevent the wearer from slipping. This auxiliary cushioning means includes a raised portion 16 extending beyond the lower tread surface 17 of the heel. The heel is provided upon its 90 upper surface with a cavity or depression 18, the portion 16 forming the lower wall of this cavity or depression. Concentrically disposed within the cavity 18 is a stop 19, in the form of a teat or lug, the upper surface 95 of which terminates short of the upper surface of the heel so as to permit the lower wall of the cavity 18 to yield under pressure. The amount of this yielding is limited by the contact of the stop with the under surface of the plate "B." As the stop 19 is formed of compressible material it will act to gradually check the inward movement of the auxiliary movement and eliminate all 100 shock or jar. 195

Having described the invention, what is claimed is:

1. A shoe heel formed of compressible material and having a cavity or depression in the upper surface thereof, a raised portion 110 forming the outer surface of the lower wall of the cavity or depression and extending

below the lower or tread surface of the heel and a solid stop located concentrically within said depression and having its upper surface disposed below the upper surrounding edge of said depression.

2. A shoe heel formed of compressible material and having a cavity or depression in the upper surface thereof, a raised portion forming the outer surface of the lower wall

of the cavity or depression and extending 10 below the lower or tread surface of the heel and a solid compressible stop located concentrically within said depression and having its upper surface disposed below the upper surrounding edge of said depression. 15

In testimony whereof I affix my signature.

FRANK WHARTON.
